COMBINED ROOM HEATER AND COOKING STOVE FOR ICE FISHING HOUSES AND THE LIKE

Thomas J. Parsons and Phillip Frisch, New Ulm, Minn.

Filed Jan. 15, 1962, Ser. No. 68,309

Term of patent 14 years

(Cl. D81—1)

FIG. 1 is a side perspective view of a combined room heater and cooking stove for ice fishing houses and the like, embodying our new design, the side opposite being a mirror image thereof;

FIG. 2 is an elevational view taken from the right side of FIG. 1 thereof;

FIG. 3 is a top plan view thereof, and

FIG. 4 is a bottom plan view thereof.

The characteristic features of our design reside in the inverted U-shaped legs and the two horizontally-disposed rectangular upper and lower heating and cooking surfaces.

We claim:

The ornamental design for a combined room heater and cooking stove for ice fishing houses and the like, as shown and described.
